GRINDING MACHINE

Herbert A. Silven, Worcester, Mass., assignor to Norton Company, Worcester, Mass., a corporation of Massachusetts

Application December 1, 1953, Serial No. 395,401

4 Claims. (Cl. 51—95)

The invention relates to grinding machines and more particularly to a cylindrical-type grinding machine for grinding work pieces of relatively large diameters.

One object of the invention is to provide a simple and thoroughly practical grinding machine for grinding large diameter work pieces. Another object is to provide a grinding machine having an L-shaped base so as to provide a control station adjacent to the point of contact between the grinding wheel and work whereby the progress of the grinding operation may be readily observed. Another object is to provide a control station whereby the longitudinal traversing of the work and the transverse movement of the grinding wheel may be readily controlled while observing the grinding operation. Another object is to provide a longitudinally movable work table with a transversely movable slide to facilitate a transverse manual adjustment of the work head supported thereby. Another object is to provide a swivel adjustment between the transverse slide and the work head. Another object is to provide a precise manually operable swivel adjusting mechanism for the work head to facilitate precise swivelling of the work head relative to the longitudinally movable carriage and the cross slide. Other objects will be in part obvious or in part pointed out hereinafter.

In the accompanying drawings, in which is shown one of various possible embodiments of the mechanical features of this invention,

Fig. 1 is a front elevation of the improved grinding machine;

Fig. 2 is a right hand end elevation of the machine;

Fig. 3 is a fragmentary vertical sectional view, on an enlarged scale, taken approximately on the line 3—3 of Fig. 2, through the work head traversing mechanism;

Fig. 4 is a fragmentary vertical sectional view, on an enlarged scale, taken approximately on the line 4—4 of Fig. 1, through the drive mechanism for the longitudinal traversing of the work head;

Fig. 5 is a fragmentary elevation, on an enlarged scale, taken approximately on the line 5—5 of Fig. 3, showing a portion of the manually operable work head traversing mechanism.

Fig. 6 is a fragmentary plan view, on an enlarged scale, with the work head removed, showing the swivelling mechanism therefor;

Fig. 7 is a fragmentary vertical sectional view, taken approximately on the line 7—7 of Fig. 6, through the pivot for the work head;

Fig. 8 is a combined hydraulic and electric diagram of the control and actuating mechanisms of the machine; and

Fig. 9 is a plan view of the grinding machine showing the L-shaped base.

A grinding machine has been illustrated in drawings comprising a base 10 which supports a wheel slide base 11 (Fig. 2). A transversely movable wheel slide 12 is supported on a V-way 13 and a flat way 14 (Fig. 1) formed on the upper surface of the wheel slide base 11. The wheel slide 12 serves as a support for a rotatable

2

wheel spindle 15 which is journaled in suitable bearings (not shown). A grinding wheel 16 is mounted at one end of the spindle 15.

A suitable driving mechanism is provided for the wheel spindle 15 and the grinding wheel 16 comprising a motor 17 mounted on the upper surface of the wheel slide 12. The motor 17 is provided with a motor shaft 18 having a multiple V-groove pulley 19 which is connected by multiple V-belts 20 with a multiple V-groove pulley 21 mounted on the right hand end of the wheel spindle 15 (Fig. 1).

A suitable feeding mechanism is provided for the wheel slide 12 comprising a half-nut 25 depending from the underside of the wheel slide 12. The half-nut 25 meshes with or engages a rotatable feed screw 26 which is journaled in suitable bearings 27 carried by a slidably mounted sleeve 28. The sleeve 28 is supported within a cylindrical aperture formed within the wheel slide base 11.

A manually operable and a power operated mechanism are provided for actuating the feed screw 26 so as to provide a manual adjustment for the wheel slide, a rapid positioning movement therefor and a grinding feed. This mechanism is substantially the same as that disclosed in the U. S. Patent No. 2,522,485 to H. A. Silven and C. G. Flygare dated September 12, 1950, to which reference may be had for details of disclosure not contained herein.

A fluid pressure cylinder 29 is provided having a slidably mounted piston 30 which is connected to one end of a piston rod 31. The other end of the piston rod 31 is connected to the slidably mounted sleeve 28. The cylinder 29 and the piston 30 are preferably arranged in axial alignment with the feed screw 26 and are arranged to cause a rapid axial movement of the feed screw 26 rapidly to move the wheel slide 12 toward and from an operative position.

A feed control valve 35 is provided for controlling the admission to and exhaust of fluid from the cylinder 29. This valve is substantially identical with that shown in the prior patent to which reference may be had for details of disclosure not contained herein. The valve 35 is a piston-type valve having a valve stem 36. A compression spring 37 surrounding the valve stem 36 serves normally to hold the valve stem 36 in a right hand end position. A solenoid 38 is provided which when energized serves to move the valve stem 36 toward the left to reverse the flow of fluid to the cylinder 29.

A fluid pressure system is provided for supplying fluid under pressure for the various actuating mechanisms of the machine. This system may comprise a motor driven fluid pump 40 which draws fluid through a pipe 41 from a fluid reservoir 42 and forces fluid under pressure through a pipe 43 to the mechanisms of the machine as will be hereinafter described. A relief valve 44 is connected in the pipe line 43 for exhausting excess fluid under pressure 55 from the pipe 43 so as to maintain the desired operating pressure within the system.

In the position of the valve 35 (Fig. 8), fluid under pressure in the pipe 43 passes through the valve 35 into a cylinder chamber 45 to move the piston 30 together with the feed screw 26 and the wheel slide 12 toward the right, that is, toward a rearward or inoperative position. During this movement fluid within a cylinder chamber 46 may exhaust through a passage 47, through a throttle valve 48 and through an exhaust pipe 49 into the reservoir 42. The throttle valve 48 serves to control the rate of movement of the piston 30 during its movement to a rearward or inoperative position. A dash pot mechanism 50 is provided for cushioning the rearward movement of the piston 30 in the end of its rearward stroke.

A manually operable mechanism is provided for actu-

ating the feed screw comprising a manually operable feed wheel 55 (Fig. 1) which is operatively connected through a gear not shown to rotate a gear 56 mounted on a rotatable shaft 57. The shaft 57 also supports a gear 58 which meshes with a gear 59 mounted on the forward end of a feed screw shaft 60 which is formed integral with the feed screw 26. It will be readily apparent from the foregoing disclosure that a rotary motion of the feed wheel 55 will be transmitted through the gear mechanism above described to rotate the feed screw shaft 60 and the feed screw 26 and thereby impart a transverse feeding movement to the wheel slide 12. The direction of rotation of the feed wheel serving to determine the direction of movement of the wheel slide. A pivotally mounted stop pawl 61 is mounted on the front of the machine base and is arranged to be engaged by an adjustable stop abutment 62 carried by the said wheel 55 to facilitate a precise positioning movement of the wheel slide 12 and the grinding wheel 16 as it is moved toward the work piece to be ground.

A feeding mechanism is also provided for producing a slow precise feeding movement of the grinding wheel during the grinding operation. In the preferred form, a hydraulically operated mechanism is provided so that the feed screw may be rotated at a controlled rate to cause a continuous infeeding movement of the grinding wheel. This mechanism may comprise a fluid pressure cylinder 65 having a slidably mounted piston 66. The upper surface of the piston 66 is provided with rack teeth 67 which mesh with a gear 68 mounted on a rotatable shaft 69. The shaft 69 also supports a gear 70 which meshes with the gear 56. It will be readily apparent from the foregoing disclosure that when the piston 66 is moved longitudinally within the cylinder 65 a rotary motion will be imparted to the feed screw 26. When fluid under pressure is passed through a pipe 71 into a cylinder chamber 72, the piston 66 will be moved toward the right (Fig. 8) to impart a counter-clockwise rotary motion to the feed wheel 55. During this movement of the piston 66, fluid within a cylinder chamber 73 may exhaust through a pipe 74.

Similarly when fluid under pressure is reversed and is passed through the pipe 74 into the cylinder chamber 73, the piston 66 will be moved toward the left (Fig. 8) to impart a clockwise rotary motion to the feed wheel 55 thereby imparting a rotary motion to the feed screw 26 in the opposite direction to cause a rearward movement of the wheel slide 12 and the grinding wheel 16.

A shuttle-type feed control valve 75 is provided for controlling the admission to and exhaust of fluid from the cylinder 65. The valve 75 is a shuttle-type valve having a slidably mounted valve member 76 having a plurality of spaced valve pistons formed integrally therewith. The valve pistons are arranged to form spaced valve chambers 81, 82, 83 and 84. The valve 75 is arranged so that when fluid under pressure is passed through a pipe 77 into an end chamber 78, and slidably mounted valve member 76 will be moved toward the right into the position illustrated in Fig. 8 during this movement fluid within an end chamber 79 is exhausted through a pipe 80. The admission to and exhaust of fluid through the pipes 77 and 80 respectively is controlled by the feed control valve 35. In the position of the valve 75, fluid under pressure is passed through the pipe 77 to shift the valve member 76 into its right hand end position so that the fluid under pressure from the pipe 43 enters the valve chamber 84, passes through a central aperture 86, into the valve chamber 82 and through the pipe 74 into the cylinder chamber 73 to move the feed piston 66 toward the left into the position illustrated in Fig. 8. During this movement of the piston 66 fluid within the chamber 72 may exhaust through the pipe 71, through the valve chamber 81, through the pipe 85 into the exhaust pipe 49 and into the fluid reservoir 42.

When the solenoid 38 is energized to shift the feed con-

trol valve 35 to initiate a rapid forward movement of the wheel slide 12, fluid under pressure is passed through the pipe 80 into the end chamber 79 to shift the valve member 76 toward the left so that fluid under pressure passing through the pipe 43 will enter the valve chamber 84, pass through the central aperture 86, into the valve chamber 82 and through a pipe 71 into the end chamber 72 to start movement of the piston 66 toward the right (Fig. 8) thereby starting a rotary motion of the feed screw to advance the grinding wheel 16 into the work piece being ground for a predetermined grinding operation.

It is desirable that the backlash in the feed mechanism parts be rapidly taken up at the start of the infeeding operation. This is preferably accomplished by a backlash control valve 90 which is a shuttle type valve comprising a valve stem 91 having a pair of spaced pistons formed integrally therewith to form a valve chamber 92. Fluid under pressure passing through either the pipe 77 or the pipe 80 enters an end chamber 93 or an end chamber 94 respectively to shift the shuttle valve member 91 into the opposite end position. During this shifting movement of the valve member 91, fluid may exhaust from the valve 75 through a pipe 97, through the valve chamber 92 and pass substantially unrestricted into the exhaust line 49 thereby facilitating a rapid movement of the piston 66 during its initial movement in either direction to take up the backlash in the feed mechanism parts. The rate of movement of the valve member 91 determines the amount of fluid that may be metered from the pipe 97 directly into the pipe 49. A throttle valve 95 is provided in the pipe line 77 to control the rate of movement of the valve member 91. A check valve 96 is provided so that fluid under pressure may bypass the throttle valve 95 to cause a rapid movement of the valve member 91 toward the right since the elimination of the backlash is of no importance on the rearward stroke of the wheel slide 12.

A throttle valve 99 is provided to control the normal exhaust of fluid from the valve 75. Fluid exhausting from the valve 75 may pass through a pipe 98, through the throttle valve 99, through a V-port 100 and into the exhaust line 49. An actuating knob 101 is provided for regulating the valve 99 so as to control the normal rate of movement of the piston 66 and thereby control the rate of grinding feed.

A suitable control mechanism is provided for initiating a grinding cycle comprising a control lever 105 which is pivotally supported by a stud 106 on the front of the machine base. The lever 105 is provided with a pair of actuating screws 107 and 108 which are arranged to actuate a start switch 109 or a stop switch 110 depending upon the direction of movement of the control lever 105. When it is desired to start a grinding cycle, the control lever 105 is rocked in a clockwise direction (Fig. 8) to close the start switch 109 thereby energizing an electric timer 111. The energizing of the electric timer 111 serves to energize the solenoid 38 to shift the said control valve 35 and thereby start a rapid approaching movement of the wheel slide 12 and the grinding wheel 16. As above described when the feed control valve 35 is shifted to start a rapid approaching movement of the wheel slide 12, fluid under pressure is passed to the backlash valve 90 and also to the valve 75 to start movement of the piston 66, first taking up backlash in the feed mechanism parts before the piston 30 reaches the end of its movement toward the left after which continued movement of the piston rotating the feed screw 26, imparts a grinding feed to the wheel slide 12 and the grinding wheel 16. After a predetermined time interval, the timer 111 times-out thereby breaking a circuit to deenergize the solenoid 38 so that the feed control valve 35 returns to the position illustrated in Fig. 8 under the influence of the released compression of the spring 37. The timer 111 may be any of the well known commercial electric timers such as for ex-

ample a Microflex timer manufactured by the Signal Electric Company of Moline, Illinois.

The grinding cycle may be terminated at any time if desired by rocking the control lever 105 in a counter-clockwise direction so that the actuating screw 108 opens the stop switch 110 thereby deenergizing the timer 111 and allowing the parts to return to the initial or inoperative position.

The base 10 also serves as a support for a longitudinally reciprocable work supporting table 115 which is slidably mounted on a flatway 116 and a V-way 117 formed on the upper surface of the base 10. The table 115 supports a transversely movable slide 118 which is adjustable transversely relative to the table 115 by means of a rotatable feed screw 119. The feed screw 119 is rotatably journaled in bearings carried by the slide 118. The feed screw 119 meshes with or engages a half-nut 120 mounted on the upper surface of the work table 115. A manually operable feed wheel 121 is arranged to rotate a gear or pinion 122 which meshes with a gear 123 keyed on the forward end of the feed screw 119 (Fig. 2). It will be readily apparent from the foregoing disclosure that a rotary motion of the feed wheel 121 will impart a transverse feeding movement to the slide 118. The slide 118 serves as a support for a platen 125 which is pivotally connected thereto by means of a pivot stud 126. The platen 125 may be swivelled angularly to facilitate adjusting the position of the axis of the work piece to be ground relative to the axis of the grinding wheel.

A pair of clamping bolts 127 and 127a pass through clearance holes formed in the platen 125. The heads of clamping bolts 127 and 127a ride in arcuate shaped T-slots 129 and 129a formed in the upper surface of the transversely movable slide 118. A clamping bolt 128 fixed to the slide 118 passes through an arcuate slot 130 formed in the platen 125. The clamping bolts 127, 127a and 128 serve to facilitate clamping the platen 125 in adjusted position.

A nut and screw mechanism is provided for precisely adjusting the position of the platen 125 relative to the slide 118 comprising a rotatable screw 131 which is journaled in a bearing 132 carried by the slide 118. The screw 131 is provided with a manually operable actuating wheel 133. The feed screw 131 meshes with or engages a nut 134 carried by the platen 125. It will be readily apparent from the foregoing disclosure that a rotary motion of the wheel 133 will impart a swivelling movement to the platen 125.

A rotatably mounted work supporting spindle 135 is journaled in bearings (not shown) carried by a work head which is adjustably mounted on the platen 125. A work supporting chuck or face plate 136 is mounted on the right hand end of the spindle 135 (Fig. 1). A suitable driving mechanism is provided for the work spindle 135 comprising an electric motor 137 adjustably mounted on the top of the work head. The motor 137 is provided with a stepped multiple V-groove pulley 138 which is connected with multiple V-belts 139 with a multiple V-groove pulley 140 mounted on a shaft 141. The shaft 141 is connected by a coupling with drive shaft 141a of a speed reducer unit 142. A driven shaft 143 of the speed reducer unit 142 is provided with a multiple V-groove pulley 144 which is connected by multiple V-belts 145 with a multiple V-groove pulley 146 mounted on the left hand end of the work spindle 135 (Fig. 1).

The work table 115 is arranged so that it may be adjusted longitudinally or reciprocated or traversed longitudinally by means of a nut and screw mechanism comprising a rotatable screw 150 which is journaled in anti-friction bearings 151 and 152 (Fig. 3) which are supported in fixed relation relative to the base 10. The feed screw 150 meshes with or engages a nut 149 depending from the under side of the table 115. A sprocket 153 is mounted on the left hand end of the feed screw 150 and is connected by a cog-belt 154 with a sprocket 155

mounted on a shaft 156 of a fluid motor 157 which is fixedly supported on the base 10 of the machine. An idler pulley 158 serves to tension the belt 154 as desired. The cog-belt 154 is preferably a commercially well known belt, such as, the Gilmer timing belt.

A suitable control mechanism is provided for the fluid motor 157 comprising a manually operable start-stop valve 160 which is preferably a rotary-type valve actuated by a manually operable handle 161. The valve 160 is arranged when in a start position to pass fluid through from the pipe 43, through the valve 160 and through a pipe 162 to a shuttle-type control valve 163. When the valve 160 is in the position illustrated in Fig. 8, fluid may exhaust from the valve 163, through the pipe 162, through the valve 160 and through a pipe 164 into the exhaust pipe 49 and the reservoir 42.

The shuttle-type control valve 163 is a piston-type valve comprising a slidably mounted valve member 165 having a plurality of valve pistons 166, 167 and 168 formed integrally therewith to form a pair of spaced valve chambers 169 and 170. When fluid under pressure is passed through a pipe 171 into an end chamber 172, the valve member 165 is moved toward the left into the position illustrated in Fig. 8. During this movement fluid within an end chamber 173 may exhaust through a pipe 174. The pipe 171 is connected with the end chamber 172 by a throttle valve 175 and a check valve 176 which are arranged so that fluid under pressure may be passed unrestricted from the pipe 171 into the end chamber 172. Fluid exhausting from the end chamber 172 is controlled by the throttle valve 175. Similarly the pipe 174 is connected by a throttle valve 177 and a check valve 178 with the end chamber 173. The check valve 178 is arranged so that when fluid under pressure is passed through the pipe 174 it may pass substantially unrestricted into the end chamber 173. Fluid under pressure exhausting from the end chamber 173 is governed by the throttle valve 177. It will be readily apparent from the foregoing disclosure that by manipulation of the throttle valve 175 and 177, the rate of shifting of the valve member 165 in either direction may be regulated as desired.

A table actuated reversing valve 180, is provided for controlling the admission to and exhaust of fluid from the valve 163. The valve 180 is a rotary-type valve which may be actuated manually by means of a manually operable handle 181 or may be actuated automatically by a pair of offset radially projecting studs 182 and 183 which are arranged in the path of a pair of adjustable table dogs 185 and 186 respectively. In the position of the valve 180 (Fig. 8) fluid from the pipe 43 passes through the valve 180 and through the pipe 171 into the end chamber 172 to move the valve member 165 toward the left at a rate controlled by the throttle valve 177. When the start-stop valve 160 is in a traverse or start position, fluid under pressure passing through the pipe 162 enters the valve chamber 170 and passes through a pipe 187 to the fluid motor 157 to start the motor rotating in one direction to cause a longitudinal traversing movement of the work table 115. During this movement fluid may exhaust from the other side of the motor 157 through a pipe 188 into the valve chamber 169, through a pipe 189 into the exhaust pipe 49 and the reservoir 42. A throttle valve 190 is provided in the pipe 189 to facilitate controlling the rate of exhaust of fluid from the motor 157 thereby to control the rate of traversing movement of the table 115. A check valve 191 is provided in the pipe 189 so that fluid may bypass around the throttle valve 190 when fluid is passed in the opposite direction.

As shown in Fig. 1 the table 115 when started will move in a direction toward the left as above described. This movement toward the left will continue until the dog 186 engages the stud 182 to shift the valve 180 in a counter-clockwise direction so that fluid under pressure from the pipe 43 will pass through the valve 180 and through the pipe 174, through the check valve 178 into

the end chamber 173 to shift the valve member 165 toward the right at a rate controlled by the throttle valve 175. With the valve member 165 in its right hand end position fluid under pressure from the start-stop valve 160 passing through the pipe 162 enters the valve chamber 169 and passes through the pipe 188 to the motor 157 to rotate the motor in the reverse direction thereby starting the table 115 moving in a direction toward the right (Fig. 1). During this movement fluid may exhaust from the motor 157 through the pipe 187, into the valve chamber 170, through the pipe 189, the throttle valve 190 into the exhaust pipe 49 and the reservoir 42.

A manually operable mechanism is provided for actuating the screw 150 to facilitate a manual traversing movement of the table 115. As illustrated in Fig. 3, a manually operable traverse wheel 200 is keyed on the right hand end of a shaft 201 which is journaled in bearings 202 and 203 carried by a casing 204. The shaft 201 is provided with a gear 205 which is arranged to be moved axially into or out of engagement or mesh with a gear 206. The gear 206 is supported by a stud 207 fixedly mounted within the casing 204. The gear 206 meshes with a gear 208 which is keyed on the right hand end of a shaft 209. The shaft 209 is journaled in an anti-friction bearing at its right hand end. The left hand end of the shaft 209 telescopes over a reduced end portion 211 of the feed screw 150 and is keyed thereto. The casing 204 is preferably adjustably mounted so that the casing together with the traversing wheel 200 may be swung in a transverse direction so that it may be maintained in close proximity to the feed wheel 55. A flange member 212 is fixedly mounted relative to the base 10 and is provided with a pair of elongated arcuate slots 213 and 214. A pair of clamping bolts 215 and 216 pass through the elongated slots 213 and 214 respectively and are screw threaded into the casing 204.

This machine is particularly intended for grinding relatively large diameter work pieces which may be mounted on a face plate or chuck for grinding peripheral faces or side faces thereon. It is desirable in a grinding operation of this type that the operator be able to visibly observe the grinding operation as it proceeds. By the provision of the substantially L-shaped base, a control station is provided whereby the operator may readily observe the grinding action of the grinding wheel 16 and may readily control actuation of the feed wheel 55, the traverse wheel 200, the cycle control lever 105 and the traverse control valve 160 while observing the grinding operation. As previously stated the casing 204 is adjustably mounted so that it may be swung about the axis of the feed screw 150 so that the traverse control wheel 200 may be positioned in a convenient location relative to the feed wheel 55.

The operation of this improved grinding machine will be readily apparent from the foregoing disclosure. A workpiece to be ground is mounted on the face plate 136, the wheel drive motor is then started and the motor for driving the pump 40 is started after which a grinding cycle may be started by actuation of the control lever 105. For a plunge cut grinding operation the table or carriage 115 remains stationary while the grinding wheel slide 12 is fed toward the periphery of the work piece to grind the same to the desired and predetermined extent. The grinding cycle may be under the control of the timer 111 or if desired may be manually controlled by opening a switch 217 thereby rendering the timer 111 inoperative. If a traverse grinding operation is desired, the control lever 161 may be shifted to start the motor 157 so as to reciprocate the table or carriage 115 through a stroke determined by the setting of the table dogs 185 and 186.

If desired the grinding operation may be performed manually by actuation of the feed wheel 55 to manually control the forward and rearward movement of the grinding wheel slide 12. The table or carriage 115 may be

reciprocated by power in a manner above described as controlled by the valve 160, or may if desired be manually controlled by actuation of the traversing wheel 200.

It will thus be seen that there has been provided by this invention apparatus in which the various objects hereinabove set forth together with many thoroughly practical advantages are successfully achieved. As many embodiments may be made of the above invention and as many changes might be made in the embodiments above set forth, it is to be understood that all matter hereinbefore set forth, or shown in the accompanying drawings, is to be interpreted as illustrative and not in a limiting sense.

I claim:

1. In a grinding machine having a substantially L-shaped base, a transversely movable wheel slide slidably supported to slide transversely on a longitudinally extending portion of the base, a rotatable grinding wheel thereon, a nut and screw feed mechanism interposed between the slide and base, means including a manually operable feed wheel rotatably supported on the front of said longitudinally extending base portion to actuate nut and screw mechanism, a longitudinally movable carriage slidably supported on the forwardly projecting portion of said base, said carriage being arranged to slide in a direction normal to the transverse movement of the wheel slide, a rotatable work support on said carriage, means including a power operated traversing mechanism interposed between said carriage and base, and a manually operable traverse wheel rotatably supported on the side of said forwardly projecting base portion which is operatively connected to actuate said traversing mechanism, a movably mounted casing adjustably supported on the end of the longitudinally movable carriage for supporting said manually operable traverse wheel, and means to adjust said casing so as to vary the position of said traverse wheel relative to the feed wheel.

2. In a grinding machine having a substantially L-shaped base, a transversely movable wheel slide slidably supported to slide transversely on a longitudinally extending portion of the base, a rotatable grinding wheel thereon, a nut and screw feed mechanism interposed between the slide and base, a manually operable feed wheel rotatably supported on the front of said longitudinally extending base portion operatively connected to actuate said nut and screw mechanism, a longitudinally movable carriage slidably supported on a forwardly projecting portion of the base, said carriage being arranged to slide in a direction normal to the movement of said slide, a rotatable work support on said carriage, means including a power actuated nut and screw traversing mechanism interposed between the carriage and base, and a manually operable traverse wheel rotatably supported on the side of said forwardly projecting base portion which is operatively connected to actuate said traversing screw, a pivotally mounted casing adjustably supported on the end of the longitudinally movable carriage for supporting said manually operable traverse wheel, and means to adjustably swing said casing so as to vary the position of said traverse wheel relative to said feed wheel, said L-shaped base serving to provide a control station in close proximity to the grinding wheel and the rotatable work support whereby the feed wheel and traverse wheel may be readily actuated while visibly observing the grinding action of the grinding wheel upon the work piece being ground.

3. In a grinding machine as claimed in claim 1, in combination with the parts and features therein specified of a transversely movable slide slidably mounted on said carriage, means including a manually operable nut and screw mechanism interposed between the carriage and slide to facilitate a transverse adjustment of the slide relative to the carriage, a work head supported on said slide, a rotatable work spindle rotatably supported on the work head having a work supporting member, pivotal connections between said slide and head including a

vertically arranged pivot stud interposed therebetween, and precision means including a manually operable nut and screw mechanism interposed between the slide and work head to facilitate precisely swivelling the work head relative to the slide.

4. In a grinding machine as claimed in claim 2, in combination with the parts and features therein specified of means including a rotary-type fluid motor operatively connected to rotate said work carriage traversing screw, means including a fluid pressure actuated reversing valve operatively connected to control the admission to and exhaust of fluid from said fluid motor, a pilot valve

5

operatively connected to actuate said reversing valve, and means including adjustable dogs on said carriage to actuate said pilot valve to facilitate controlling the reciprocatory stroke of the work carriage.
